Patented Nov. 1, 1910.

UNITED STATES PATENT OFFICE.

WILLIAM M. PRUETT, OF GREENSBORO, NORTH CAROLINA, ASSIGNOR OF ONE-HALF TO
WILLIAM A. BYERLY, OF BRIDGEWATER, VIRGINIA.

ICE-MAKING MACHINE.

974,184.

Specification of Letters Patent.

Patented Nov. 1, 1910.

Application filed December 30, 1909. Serial No. 535,687.

To all whom it may concern:

Be it known that I, WILLIAM M. PRUETT, a citizen of the United States, residing at Greensboro, in the county of Guilford and 5 State of North Carolina, have invented a new and useful Ice-Making Machine, of which the following is a specification.

This invention relates to refrigerating, cooling or ice machines of the compression 10 type, and has for one of its objects to provide an extremely simple, inexpensive, practical and efficient machine of this character which is especially designed for domestic, hotel, institutional and other uses, where economy 15 and simplicity in the running of the machine are highly essential, the machine being capable of management by unskilled persons, since the only attention required after the machine is once installed, is the throwing 20 on or off of the power for driving the compressor, the filling of the ice cans and the removing of the ice.

Another object of the invention is to utilize the refrigerating medium for keeping 25 the compressor cylinders cool to insure the proper working of the pistons and also for obtaining a compressed gas at a lower temperature than can be attained in the machines heretofore used, and to carry out this 30 feature, the refrigerating medium, which is preferably a gas that can be readily liquefied at a relatively low pressure with a minimum of power and which is non-explosive under pressure or not inimical to life in case of 35 leakage, is by-passed through the cooling jackets of the compressor cylinders after it has traversed the cooling coils in the brine tank, and is drawn into the compression chambers of the cylinders through passages 40 in the walls of the latter, so that there will always be a full charge of gas to be compressed, even if the suction valve in the piston should, for any reason, stick on its seat. It will be understood, however, that gas will 45 be admitted to the cylinders through the usual piston suction valves from the cooling coils by a return pipe leading from the latter to the suction chambers of the cylinders, and the flow of gas through such pipe will 50 be controlled by valves so that a full charge cannot be admitted through the suction valves and consequently the passage of gas from the cooling jackets to the cylinders to make up the full charge will be assured.

Another object of the invention is the employment of a storage tank for the refrigerating agent such for instance as sulfur dioxide, which tank is connected between the cooling coils and compressor so as to act as an accumulator whereby an available supply 55 of gas will always be present to compensate for leakage and thus avoid re-charging throughout the life of the machine. By a suitable arrangement of valves, the gas can be removed from all parts of the system 60 by the operation of the pump and stored in the tank, so that repairs can be effected without losing the refrigerating agent, as is now necessary with ice making machines, and furthermore, whenever the machine is shut 65 down, the gas can be confined in the tank so that there is no chance of gas leaking from the system, and another advantage is that the compressor can be more readily started when the pistons do not have the pressure 70 of the gas to overcome.

With these objects in view and others, as will appear as the description proceeds, the invention comprises the various novel features of construction and arrangement of 80 parts which will be more fully described hereinafter and set forth with particularity in the claims appended hereto.

In the accompanying drawing, which illustrates one embodiment of the invention, 85 the figure is a diagrammatic view of the ice making, refrigerating or cooling machine, showing a portion of the compressor in section.

Referring to the drawing, A designates a 90 compressor which is preferably made in two sections 1 and 2, each composed of separate cylinders c and c' having pistons 2a. The pistons are connected by rods 3 with cross heads 4 and the latter are connected by rods 95 5 with a four-throw crank shaft 6, which shaft is driven in any suitable manner, as for instance, by a pulley 7 around which passes a driving belt 8. By this arrangement, more even running is insured than 100 with a single or double cylinder compressor. Each section of the compressor has the lower ends of its cylinders opening into suction chambers 9 which are provided with stuffing boxes 10 through which the piston 105 rods reciprocate, and the heads of the cylinders are provided with ports 11 controlled by spring compressed discharge valves 12.

The ports 11 communicate with a common outlet chamber 13 which is connected with a discharge pipe 14 equipped with a cut-off valve 15 and a pressure gage 16. The cylinders of each section are surrounded by a cooling jacket 17 that extends over the heads of the cylinders to cool the parts which are heated by the compression of the gas. The walls of the cylinders are provided with one or more passages 18 which have ports 19 communicating with the cooling jacket and ports 20 that are adapted to communicate with the piston chambers of the cylinders, the ports 20 being so arranged as to be uncovered by the pistons when the latter have reached the limits of their strokes. The pistons are hollow and each is provided with a valve 21 that opens inwardly to admit gas from the chamber 9 to the cylinder space above the piston, so that a charge of gas will be admitted to the cylinder both through the piston and through the passages 18. It will thus be seen that if the piston valves stick, for any reason, as in starting the compressor after it has been shut down, the gas will pass into the cylinder directly from the cooling jacket. The compressor can operate in this manner effectively until the parts become heated and the valve loosened from its seat, when gas will be also drawn in through the piston from the suction chamber 9.

The pipes 14 of the two sections of the compressor unite in a single pipe 22 which conducts the relatively hot compressed refrigerant through an ordinary condenser 23 through which water flows by the pipes 24 and 25. The cooled refrigerant passes out of the condenser through the pipe 26 having the valve 27 and connected with the header 28. This header 28 connects with a manifold 29 at separate points and is provided with expansion valves 30 of the usual construction, the manifold 29 supplying expanded gas to the cooling coils 31, submerged as usual in the brine tank. The discharge end of the coils is connected with a manifold 32 from which the refrigerant flows through a return pipe 33, the coils having individual valves 34 for cutting them into or out of the system, as required. The return pipe 33 is provided with branches 34 and 35 that connect respectively with the suction chambers 9 of the sections 1 and 2 of the compressor, so that both sections of the latter will draw the gas from the cooling coils. In each branch of the return pipe is arranged a storage tank T for the gas, and the pipes are provided with cut-off valves 36 and 37 at the inlet and outlet sides of the tanks. In one branch of the return pipe, provision is made for charging the system with gas, such for instance as a nipple 38 to which a connection may be made with the charging carboy, this nipple

being provided with a valve 39 which is normally closed when the machine is in operation, and between the point where the nipple connects with the pipe 35 and the compressor, is a valve 40. All the gas is not returned from the coil through the branches 34 and 35, but a by-pass is provided consisting of a pipe 41 connected with the return pipe 33 and having branches 42 and 43 connected with the cooling jacket 17 of the compressor sections, and these branches have controlling valves 44.

In the discharge pipe 22 is arranged a valve which provides a vent when the system is to be exhausted for the purpose of charging, and for this purpose, a three-way valve 45 will be employed which, when its handle is in the full line position, provides an outlet to the atmosphere through a pipe 46, and when in the dotted line position, closes the vent and permits the refrigerant to pass through the condenser.

In charging the apparatus, the three-way valve 45 is opened so that the discharge side of the compressor will be in communication with the atmosphere while the suction side of the system will be closed or cut out of communication with the atmosphere from the condenser to the suction chambers of the compressor sections. The compressor is now started and as a result, the air is drawn out from the coil of the condenser 23, cooling coils 31, tanks T, suction chambers 9, cooling jackets 17, and the various connecting pipes, and when the pressure, as indicated by the gage 47, is sufficiently low, the valve 39 of the charging nipple 38 connected with the charging carboy will be opened, and as a consequence, the gas will flow into the air-evacuated portion of the system. The three-way vent valve 45 will, of course, be closed to prevent loss of gas, and when a sufficient quantity of gas has been supplied from the carboy, the charging valve 39 is closed when the system will be ready to operate. In operation, the gas enters the cylinders from the suction chambers 9 upon the opening of the piston valves, and when each piston reaches the end of its stroke, gas will enter either cylinder or suction chamber by the passages 18 from the cooling jacket, since the ports 19 of said passages are always open. The valves 37 and 44 will be so relatively adjusted that the gas will be drawn into the piston chambers from the cooling jacket to insure a circulation of gas through the jacket to act as a cooling medium in the latter. On the compression stroke, the gas is condensed and discharged through the port 11 to the chamber 13, and thence flows through the pipes 14 and 22 to the condenser. The cooled refrigerant thence passes to the expansion valve which expands and delivers the gas to the refrigerating coils, and after traversing these coils, the gas is simulta- 130

neously conveyed to the cooling jackets and storage tanks by the pipes 41 and 35, respectively. The storage tanks are employed to provide a reserve supply of gas to compensate for leakage so that after the machine is once charged, it can run indefinitely. By use of the tanks, the gas can be removed from all parts of the system and stored in the tanks when the machine is shut down over night, so that there will be no gas in the cylinders to cause corrosion or sticking of the valves, and also by confining the gas in the storage tanks, repair or renewal of any part of the apparatus can be effected without requiring the gas to be exhausted from the system and lost. In confining the gas in the storage tanks, it is merely necessary to close the valves 36 and 44, while the compressor continues to operate so as to pump all of the gas into the coils. The valve 15 is then closed and repairs to the condenser or storage tanks can be made. If the expansion valves be opened, the gas will gravitate, as it were, into the refrigerating coils as the gas seeks the coldest point. The expansion valves are then closed, the valve 15 opened, and the compressor is again started to create a vacuum in the storage tanks, and after this vacuum is produced, the valves 37 are closed and the valves 36 opened. Owing to the gas being under pressure in the refrigerating coils and there being a vacuum in the storage tank, it is obvious that the gas will rush into the tanks, and this action may be enforced by continuing the operation of the condensers until the pressure gages 16 and 47 indicate the desired condition. When the gas has been thus caught in the storage tanks, the valves 36 will be closed and there will then be no danger of gas leakage or corrosion of the cylinders, pistons and valves of the compressor. When the gas is stored in the tank in this manner, as in shutting down the machine, it will, of course, be easier to start the compressor when the machine is to be again used because there will be comparatively little pressure in front of the pistons to be overcome. When the compressors are again set in motion, the valves 36, 37 and 44 are opened and the necessary circulation of the gas immediately obtained. From the foregoing description, taken in connection with the accompanying drawing, the advantages of the construction and of the method of operation will be readily apparent to those skilled in the art to which the invention appertains, and while I have described the principle of operation of the invention, together with the apparatus which I now consider to be the best embodiment thereof, I desire to have it understood that the apparatus shown is merely illustrative, and that such changes may be made when desired as are within the scope of the claims appended hereto.

Having thus described the invention, what I claim as new, and desire to secure by Letters Patent, is:

1. In a machine of the class described, the combination of a compressor having a discharge at one end only, a condenser connected therewith for cooling the refrigerating medium supplied by the compressor, a cooler connected with the condenser, an expansion valve between the condenser and cooler, a return conduit between the cooler and compressor, a cooling jacket for the compressor, and means for by-passing a portion of the refrigerating medium through the jacket from the return conduit and admitting the remainder of the medium directly to the compressor.

2. In a machine of the class described, the combination of a compressor, a condenser connected therewith for cooling the refrigerating medium supplied by the compressor, a cooler connected with the condenser, an expansion valve between the condenser and cooler, a return conduit between the cooler and compressor, a cooling jacket for the compressor, controllable means for by-passing a portion of the refrigerating medium through the jacket from the return conduit, and a storage tank included in the return conduit.

3. In a machine of the class described, the combination of a compressor, a condenser connected therewith, a cooler connected with the condenser, an expansion valve between the condenser and cooler, a return pipe leading from the cooler to the suction side of the compressor, a storage tank in the return pipe, a cooling jacket for the compressor, a pipe leading from the return pipe to the cooling jacket, valves in the said pipes for controlling the supply of the refrigerating medium to the cooling jacket, and means for conducting the medium from the cooling jacket to the piston chamber of the compressor.

4. In a machine of the class described, the combination of a compressor having a plurality of cylinder sections, a condenser, a refrigerant supply pipe leading from the cylinder sections to the condenser, a cooler, an expansion valve between the cooler and condenser, storage tanks adapted to contain refrigerating medium, a return pipe leading from the cooler to both storage tanks, means connecting the tanks with the cylinder sections, cooling jackets for the cylinder sections, a pipe leading from the return pipe to both cooling jackets, valves in the last-mentioned pipe for controlling the supply of the refrigerating medium to the individual jackets, and means for conducting the refrigerating medium from the cooling jackets of the cylinder sections to their piston chambers.

5. The combination of a compressor in-

cluding a cylinder, a piston mounted therein, a suction valve for admitting gas to the cylinder through the piston, a discharge valve, a cooling jacket surrounding the cylinder, and communicating means between the jacket and cylinder opened and closed by the piston for admitting gas from the jacket to the cylinder, with a condenser for receiving a refrigerant from the compressor, a cooling coil, an expansion valve between the condenser and coil, and separate means for conducting the gas from the cooling coil to the compressor jacket and the suction valve of the compressor.

6. The combination of a compressor including a cylinder, a piston mounted therein, a suction valve for admitting gas to the cylinder through the piston, a discharge valve, a cooling jacket surrounding the cylinder, and communicating means between the jacket and cylinder opened and closed by the piston for admitting gas from the jacket to the cylinder, with a condenser for receiving a refrigerant from the compressor, a cooling coil, an expansion valve between the condenser and coil, a return pipe leading from the cooling coil to the suction valve of the compressor, a controlling valve in the return pipe for regulating the supply of gas to the compressor, a by-pass leading from the return pipe to the cylinder jacket, and a controlling valve in the by-pass.

7. The combination of a compressor including separate cylinders, discharge valves in the cylinders, pistons reciprocating in the cylinders, valves in the pistons admitting

gas to the cylinders through the pistons, a suction chamber for each of the cylinders, a return pipe connected with the suction chambers, a cooling jacket surrounding the cylinders, and conduits in the walls of the cylinders connecting the cooling jacket with the cylinders, said conduits having their discharge ends arranged to be uncovered by the pistons when the latter reach the outer limits of their strokes for admitting gas from the cooling jacket to the cylinders, with a condenser connected with the compressor, a cooler connected with the condenser and with the said return pipe, an expansion valve between the condenser and cooler, a valve in the return pipe, and means for conducting gas from the cooler to the cooling jacket and thence through the said conduits to the cylinders.

8. The combination of a compressor including a cylinder and piston, and a cooling jacket surrounding the cylinder and opening directly into the same, with a condenser connected with the compressor, a cooler connected with the condenser, an expansion valve between the cooler and condenser, and means for returning part of the gas to the cylinder of the compressor through the jacket thereof and the rest of the gas to the cylinder independently of the jacket.

In testimony, that I claim the foregoing as my own, I have hereto affixed my signature in the presence of two witnesses.

WILLIAM M. PRUETT.
